UNITED STATES PATENT OFFICE.

HARRY B. HILLS, OF TOMPKINSVILLE, NEW YORK, ASSIGNOR TO STEWARD DAVIT & EQUIPMENT CORPORATION, OF NEW YORK, N. Y., A CORPORATION OF NEW YORK.

HOISTING MECHANISM.

1,367,142.

Specification of Letters Patent.

Patented Feb. 1, 1921.

Application filed December 19, 1919. Serial No. 346,013.

To all whom it may concern:

Be it known that I, HARRY B. HILLS, a citizen of the United States, residing at Tompkinsville, in the county of Richmond and State of New York, have invented certain new and useful Improvements in Hoisting Mechanisms, of which the following is a specification.

My invention relates to hoisting mechanisms such as are commonly used for raising and lowering a load, as for example a life boat. I will describe a hoisting mechanism embodying my invention, and then point out the novel features in claims.

In the accompanying drawings, Figure 1 is a top plan view of a hoisting mechanism embodying my invention and showing its use in connection with a pair of ship's davits to launch and deck a life boat. The ship's davits are shown in cross-section. Figs. 2 and 3 are detail views of the hoisting mechanism shown in Fig. 1. In Fig. 2 the section is on the line 2—2 of Fig. 3, and in Fig. 3 the section is on the line 3—3 of Fig. 2, the two sections being in planes at right angles to each other.

Similar reference characters designate corresponding parts in all of the figures.

Referring to Fig. 1, A designates a life boat which rests upon a deck of a vessel between ship's davits B, B. The davits B, B, may be of any desired construction, an example of which is shown in U. S. Patent No. 1,245,752 granted to T. H. Marten, December 24, 1914. The function of the davits B, B, is to carry the boat A outboard to a position from which it can be lowered into and raised out of the water. C designates a mechanism for raising and lowering the life boat from the davits. It comprises a reel c for the ropes or falls c¹, c². One rope c¹ passes from one portion of the reel c around blocks c³, c⁴, secured to the deck, around a block carried by the eye of the first davit (not shown) and to one end of the life boat A. The other rope c², passes around a block c⁵ secured to the deck, around a block carried by the eye of the second davit (not shown) and to the other end of the life boat.

Referring now to Figs. 2 and 3 which show details of the hoisting mechanism, the reel c is secured to a shaft d which is suitably journaled in a pair of standards d¹, which are joined together by cross-pieces d² for

the purpose of forming a stiff support. The reel c is provided at one end with a gear e or that end of the reel may be formed with gear teeth, with which meshes a gear e¹ fixed on a shaft e² which is suitably journaled in brackets e³ secured to the standards d¹. A pair of cranks e⁴ may be employed for rotating the shaft e² when it is desired to lift a life boat from the water onto the deck of the vessel.

F designates a brake drum which is loosely mounted on the shaft d¹, roller or other anti-friction bearings being provided between the drum and shaft. The usual brake band f is provided on the braking surface of the drum, and the usual control lever f¹ carrying the weight w is also provided for the brake band. The inner surface of the brake drum is provided with ratchet teeth f², with which coöperate pivoted pawls f³ carried by the reel c. As will be seen from Figs. 2 and 3, the drum is open at the side adjacent the reel c so that the pawls can coöperate with the ratchet teeth f². Stops f⁴ are provided for limiting the movement of the pawls on their pivots and thus insure their engagement with the ratchet teeth f².

The operation of the hoisting mechanism is as follows—When a load is to be lowered the reel c and brake drum F rotate together in the direction of the arrow x (Fig. 3). This is so because in this direction of movement the lower pawls f³ are in engagement with the ratchet teeth f². In this direction of rotation the lowering of the load is directly under the control of an operator through the control lever f¹ and brake-band f. After the load has been lowered, in this instance the life boat, the ropes are detached therefrom. The ropes or falls are then recovered by applying the cranks to the squared ends of the shaft d and rotating the reel c directly instead of through the gear c¹. In this operation the control lever f¹ is released, and the weight w imposes sufficient pull on the brake band to hold the brake drum against rotation. Therefore the reel c being rotated in a direction opposite to that indicated by the arrow, the pawls f³ ride idly over the ratchet teeth f². After the ropes or falls are recovered another boat or load may be lowered as before described.

Having thus described my invention what I claim as new is:—

1. In combination, a reel; gear teeth 110

- thereon by means of which it is rotated in one direction; a plurality of gravity operated pawls carried by said reel and equally spaced apart; a drum adjacent the reel; 5 ratchet teeth carried by the drum and with which any one or more of the pawls engage to cause the reel and drum to move together in one direction of rotation of the reel; and a brake band surrounding the drum.
- 10 2. In combination, a reel; gear teeth thereon; gravity operated pawls carried by the reel; a brake drum having an open side

adjacent the reel; ratchet teeth carried by the drum and with which the pawls engage through said open side to cause the reel and 15 brake drum to rotate together; and means for holding the brake drum against movement in one direction of rotation of the reel.

HARRY B. HILLS.
